LOW TEMPERATURE CENTRIFUGAL SWITCH
John Gilbert Ray, Mineola, N.Y., assignor, by mesne assignments, to Sylvania Electric Products Inc., Wilmington, Del., a corporation of Delaware
Filed Aug. 31, 1951, Ser. No. 244,609
6 Claims. (Cl. 200—152)

This invention relates to a mercury unshorter switch and more particularly to a low temperature centrifugal type of switch.

The prior art is well aware of various types of switches in which mercury is used to make or break the contact. It is also aware of the centrifugal type of switch in which the mercury is caused to pass through a porous plate before it can leave the chamber in which it functions as the electrical conducting medium between two leads. These switches of the prior art are however limited in their use to certain temperature conditions which are not always present where these switches are to be used. This is particularly true in very cold climates. There has, therefore, been an apparent need for the development of a low temperature centrifugal type unshorter switch for some time.

An object of this invention is, therefore, to provide a mercury switch which is suitable for use at extremely low temperatures.

A further object of this invention is to provide a method for making a switch which will function at extremely low temperatures and which will meet the rigid specifications laid down for the normal centrifugal type unshorter switches.

In accordance with this invention it has been found that these and other advantages incidental to its application can be obtained by replacing the mercury in the switch with a mercury amalgam which has a freezing point lower than that of mercury.

In the drawings which illustrate an embodiment of the features of this invention—

FIGURE 1 is a front elevation partly in section of a sub-assembly of the switch showing the cup-shaped member sealed to the porous filter disc.

FIGURE 2 is a front elevation of a switch showing the cup and filter disc sealed to a member through which two electrical conducting leads insulated from one another project into the lower chamber and are surrounded with mercury.

A specific embodiment of the centrifugal type of switch illustrated in the drawings consists of a metallic eyelet 10 which is preferably made of a material suitable for sealing to glass such as the iron nickel or iron nickel chromium alloys which are frequently used in the electronics industry for this purpose. The bottom end of this eyelet is sealed off with a suitable glass 12 through which two spaced contact leads 14 pass. The top of the eyelet is sealed to a cup-shaped metallic element 20 with a filter disc 18 sealed therebetween in a manner to separate the entire unit into two separate chambers. The lower chamber as shown in FIGURE 2 at 16 contains mercury whereas the upper chamber is provided with a number of glass balls 26 and a small pellet of thallium metal.

Although it has been known for some time that a mercury thallium amalgam containing approximately 9% thallium has a freezing point of minus 59° C., this material could not be simply used to replace the mercury in the mercury unshorter switches because of the fact that both thallium and the mercury thallium amalgam oxidize quite readily in the air and such oxide film would result in the formation of a heavy scum which is detrimental to the operation of an unshorter switch.

In accordance with this invention it has however been found that this amalgam can be used for this purpose

2

if it is found in the switch after the switch has been evacuated. In accordance with a preferred embodiment of this invention this can be accomplished in the following manner. The sub-assembly as shown in FIGURE 5 1 is first made by taking a metallic cup 20 and placing therein a measured amount of thallium 22 which has preferably been cleansed in nitric acid and coated with a lacquer film 24. Along therewith is introduced a quantity of glass beads or other ceramic pellet material whereupon a filter disc 18 is spot welded to the cup. A measured amount of mercury 16 is then placed into a unit which has been formed from a metallic eyelet 10 sealed at one end and with a glass bead through which pass two spaced conductors 14. The sub-assembly is then placed 10 in position and the two units welded together. This is preferably carried out in an evacuated atmosphere in order that any gases present in the unit may be exhausted prior to the actual sealing operation. After the seal has been made the switch is placed in a centrifugal spinner 15 where it is spun in such manner as to cause the mercury to pass through the filter mechanism into the cup 20. Meanwhile the heat given off during the welding operation will have caused the lacquer 24 to decompose and deposit carbonaceous material on the end of the cup. 20 The mercury can thereby readily get in contact with the thallium and form an amalgam therewith. The switch is then preferably vibrated so as to cause the glass balls to oscillate throughout the amalgam. Since the glass has a natural affinity for any scum which may be present it 25 removes it from the amalgam. Thereupon the switch is again placed into a spinning mechanism which causes the amalgam to pass through the filter disc into the lower chamber and provide a switch which is ready for use.

A switch of this type is well adapted for use at temperatures below minus 40° C. where a small time delay is desired.

While the above description and drawings submitted herewith disclose a preferred and practical embodiment of the switch of this invention it will be understood that 40 the specific details of construction and arrangement of parts as shown and described are by way of illustration and are not to be construed as limiting the scope of the invention.

What is claimed is:

- 45 1. A low temperature type switch having as its fluid type electrical conducting constituent a mercury thallium amalgam.
2. A low temperature mercury type switch having as its fluid type electrical conducting constituent a mercury thallium amalgam containing about 9% thallium.
- 50 3. The method of making a low temperature centrifugal type switch having a plurality of chambers separated by a porous disc comprising assembling the components with a thallium pellet in one chamber and mercury in another, exhausting the air from the chambers, sealing the chambers from the atmosphere, spinning the switch to cause the mercury to flow through the porous disc and amalgamate with the thallium and spinning the switch with the chambers reversed to cause the amalgam to seep 55 through the porous disc and return to the first chamber.
- 60 4. The method of making a low temperature centrifugal type switch having a plurality of chambers separated by a porous disc comprising assembling the components with a lacquer coated thallium pellet in one chamber and mercury in another, exhausting the air from the chambers, sealing the chambers from the atmosphere and breaking down the lacquer coat on the thallium, spinning the switch to cause the mercury to flow through the porous disc and amalgamate with the thallium and spinning the switch 65 with the chambers reversed to cause the amalgam to seep through the porous disc and return to the first chamber.
- 70

5. The method of making a low temperature centrifugal type switch having a plurality of chambers separated by a porous disc comprising assembling the components with a lacquer coated thallium pellet and glass beads in one chamber and mercury in another, exhausting the air from the chambers, sealing the chambers from the atmosphere and breaking down the lacquer coat on the thallium, spinning the switch to cause the mercury to flow through the porous disc and amalgamate with the thallium, shaking the beads through the amalgam to remove any scum and spinning the switch with the chambers reversed to cause the amalgam to seep through the porous disc and return to the first chamber.

6. The method of making a low temperature centrifugal type switch having a plurality of chambers separated by a porous disc comprising assembling the components with a lacquer coated nitric acid cleaned thallium pellet
